HOLDING DEVICE

Homer C. Warner, Cleveland, Ohio, assignor to
The Lees-Bradner Company, Cleveland, Ohio,
a corporation of Ohio

Application May 26, 1949, Serial No. 95,542

5 Claims. (Cl. 90—59)

1

This invention relates to a holding device which is particularly applicable to machine tools.

An object of the invention is to provide an improved holding device which will be very simple in operation.

Another object is to provide an improved holding device which will hold articles very accurately in position.

Another object is to provide an improved holding device which may be operated with little effort.

Another object is to provide an improved holding device which will provide a firm and positive support.

Another object is to provide an improved holding device which will be composed of few and simple parts.

Another object is to provide an improved holding device which will be extremely rugged in construction.

Another object is to provide an improved holding device which may easily and economically be manufactured.

Another object is to provide an improved holding device which may easily be applied to machine tools of various types.

The invention will be better understood from the description of one practical embodiment thereof, illustrated in the accompanying drawings, in which

Figure 1 is a plan view of a type of steady rest embodying my invention, this rest being especially designed for use on vertical hobbing machines.

Figure 2 is a transverse sectional view of the rest of Figure 1 taken on a plane parallel to and below that of Figure 1 at the level indicated by the line II—II of Figure 3.

Figure 3 is a side elevational view taken on the line III—III of Figure 1.

Figure 4 is a fragmentary end elevational view taken on the line IV—IV of Figure 1, and

Figure 5 is a fragmentary transverse sectional view taken on the line V—V of Figure 1.

While the device is shown as designed for use on vertical hobbing machines and for holding a steady rest for cylindrical pieces, it will be obvious as the description proceeds that it may be used on many other types of machine tools and that it may be placed in other positions than those shown, as the various devices to which it is applied may require, without any essential modification of its working parts.

In the form illustrated, the device is supported on a bracket 1 having bearing surfaces 2, 3, 4 and 5 arranged to locate the bracket upon the part of the tool to which it is applied. In the form illustrated, these surfaces are arranged to engage the vertical tail stock ways of the hobbing machine. To these ways the bracket may be secured in any desired manner, as by a bolt passing through an aperture 6 through the bracket.

Fixed to the outer vertical face of the bracket, as by machine screws 7, is a generally channel-

2

shaped block or frame consisting of web 8 and parallel flanges 9 and 10. The open side of the channel-shaped frame is closed by a plate or cover 11, secured to the flanges by machine screws 12, so that a horizontal generally rectangular space is provided within the frame, this being somewhat enlarged centrally thereof, as indicated at 13, by the cutting away or reduction in thickness of the flanges 9 and 10, for a purpose which will become apparent as the description progresses.

To permit access to the machine screws 7, perforations 14 are formed through flange 10, and to exclude dirt from entering these perforations, 15 their outer ends are counterbored and closed by expandable plugs 15.

Journaled in the cover 11 is a bushing 16 through which passes a shaft 17, the shaft being shown as keyed to the bushing by a Woodruff key 18.

Formed unitarily with the shaft 17 is a cam 19, which, as best seen in Figure 2, is a single lobed cam having a dwell 20 at its minimum radial distance from the axis of its shaft and another dwell 21 at its maximum radial distance therefrom, these both being of substantial extent and joined by generally spiral surfaces.

The shaft 17 extends beyond the cam and is provided on its end remote from the bushing 16 with a thread 22, which engages the internal thread of a generally gland shaped bushing 23 fitting into an aperture in web 8 of the frame.

The bushing 23 is held against rotation by a machine screw 24, and its axial position within the aperture of web 8 is controlled by this machine screw and a set screw 25, these both passing through the flange portion of the gland shaped bushing 23, the set screw 25 having threaded engagement therewith.

Longitudinally slideable within the channel-shaped frame is a slide or crosshead consisting of two rectangular ends 26 and 27 which substantially fill the space within the frame and are joined by a narrower central portion 28 formed unitarily with these ends 26 and 27.

45 This central portion 28 has an elongated slot 29 through which shaft 17 extends, and which permits the slide to travel a limited distance without interference with the shaft.

Block 27 has formed in it an aperture extending generally perpendicularly to the axis of shaft 17, the outer portion of the aperture being enlarged and threaded to receive the threaded head 30 of a bearing shoe or abutment 31, and also to receive a short set screw 32 for locking the threaded portion 30 in adjusted position. It will be noted that the shoe 31 bears upon the right hand side of cam 19 as shown in the drawings.

60 Rectangular end 26 of the slide is provided with an aperture, substantially in alignment with that in end 27, shown as having an enlarged counterbored portion in which slides the hollow cylindrical end 33 of a second bearing shoe or

abutment 34, engaging the side of cam 19 diametrically opposite to abutment 31.

Within and extending beyond the hollow of head 33 is a helical compression spring 35, the outer end of which bears upon the work-supporting shoe 36, this shoe being fixed to end 26 by machine screws 31.

The outer end of shoe 36 is formed into a shape for engaging the work piece, shown in the drawings as a semi-cylinder having a lining 38 of bearing material which actually contacts with the work piece W.

The outer end of shaft 17 is threaded as indicated at 39 for the reception of a nut 40, which retains a lever or crank 41, provided with a handle 42, the lever being secured to bushing 16 to rotate therewith by a pin 43, the pin being selectively engageable with any of a plurality of circularly arranged holes in the bushing so that the handle may be set in any desired angular position for convenient manipulation, by simply loosening the nut 40.

The operation of the device is as follows:

With the parts assembled as shown in the drawings, the operator rotates the handle in a counterclockwise direction as seen in Figure 1, substantially half a revolution from the position in which it appears in this figure, which swings the lobe of the cam to the right, moving the slide 26, 27, 28 to the right and retracting the shoe 36 from the work piece W.

After replacing the work piece, he rotates the handle in a clockwise direction, returning it to the position in which it is shown in the drawings. This swings the cam to the position shown in Figure 2, the spiral portion of the cam bearing upon abutment 34 and moving the slide and associated parts to the left, so that the shoe 36 engages the new work piece W.

Should the work piece be slightly oversize, pressure of the shoe upon it will compress the spring 35, permitting the slide to travel a slightly shorter distance to the left and thus compensates for such variation in size.

The latter part of this clockwise rotation of the shaft 17 causes the threads at 22 to draw the shaft 17 to the right (as seen in Figure 5) through the engagement of these threads with the bushing 23, and this in turn draws the bushing 16 toward and against slide portion 28, the increased pressure and consequent friction between this slide portion and the bushing serving as a friction brake to lock the parts in position.

Obviously this friction brake is released when the operator again moves the handle in a counterclockwise direction, and due to the substantial extent of the dwells 20 and 21, this braking action is entirely eliminated before abutments 31 and 34 are engaged by the interdwells portions of the cam which move the slide.

While I have described the illustrated embodiments of my invention in some particularity, obviously many other embodiments, variations, and modifications will readily occur to those skilled in this art, and I do not, therefore, limit myself to the precise details shown and described herein, but claim as my invention all embodiments, modifications and variations coming within the scope of the appended claims.

I claim:

1. A holding device comprising a frame having guide ways, a slide movable along the guide ways, a rotatable cam having a substantial dwell engaging the slide, rotating means connected to said cam for rotating the same, locking means

actuated by said rotating means while a portion of the dwell of the cam is in engagement with the slide, the slide having opposed abutments engaging opposite sides of the cam, and resilient means interposed between one of said abutments and said slide.

2. A holding device comprising a frame having guide ways, a slide movable along the guide ways, a rotatable cam having a substantial dwell engaging the slide, rotating means connected to said cam for rotating the same, locking means actuated by said rotating means while a portion of the dwell of the cam is in engagement with the slide, the slide having opposed abutments engaging opposite sides of the cam, and resilient means interposed between one of said abutments and said slide, the other abutment being adjustably fixed in and carried by the slide.

3. A holding device comprising a frame having guide ways, a slide reciprocable in said guide ways, a shaft journaled for rotary movement in the frame, a cam carried by the shaft and engaging the slide, said slide having an elongated opening therein for receiving said shaft, bushings in the frame for supporting said shaft, and threaded means carried by the shaft, one of said bushings having a slide-engaging surface for frictionally engaging the same to lock the slide in the frame upon rotation of the cam and the shaft to a predetermined position.

4. A holding device comprising a frame having guide ways, a slide reciprocable in said guide ways, a shaft journaled for rotary movement in the frame, a cam carried by the shaft and engaging the slide, said slide having an elongated opening therein for receiving said shaft, bushings in the frame for supporting said shaft, threaded means carried by the shaft, one of said bushings having a slide-engaging surface for frictionally engaging the same to lock the slide in the frame upon rotation of the cam and the shaft to a predetermined position, said threaded means carried by the shaft comprising a bushing threaded on an end of the shaft and movable axially in said frame, and means carried by said bushing to position the same axially with respect to the frame.

5. A holding device comprising a frame having guide ways, a slide movable along the guide ways, a rotatable cam having a substantial dwell engaging the slide, rotating means connected to said cam for rotating the same, and locking means actuated by said rotating means while a portion of the dwell of the cam is in engagement with the slide, said locking means including a cam shaft, bushings in the frame for supporting said shaft rotatably therein, one of said bushings having a flat frame engaging surface for frictionally engaging the same whereby to lock said slide in a predetermined position in said frame.
